Primary Examiner — Barbara Fox

Assistant Examiner — Jane Yoon

(57) **CLAIM**

The ornamental design for a suitcase, as shown and described.

DESCRIPTION

FIG. 1 is a front, right and top perspective view of a suitcase showing my new design;

FIG. 2 is a rear, left and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view of a portion labeled as 9 on FIG. 1.

The long dash-short dash broken lines shown in FIGS. 1 and 9, which form no part of the claimed design, encircle portions of the suitcase that are illustrated in enlargements.

1 Claim, 9 Drawing Sheets
